UNITED STATES PATENT OFFICE.

CHARLES M. MARKHAM, OF CHICAGO, ILLINOIS.

SUPPORT FOR CONCRETE FORMS.

Specification of Letters Patent. Patented June 7, 1910.

960,657.

Application filed January 30, 1909. Serial No. 475,245.

To all whom it may concern:

Be it known that I, CHARLES M. MARKHAM, a citizen of the United States, residing at Chicago, county of Cook, and State of Illinois, have invented certain new and useful Improvements in Supports for Concrete Forms, of which the following is a specification.

My invention relates to forms for concrete construction and more specifically to supports for such as are used in the concrete construction of floors and floor beams or girders.

The object of my invention is to provide a form support of the character mentioned which will be of such improved construction as to be adjustable, adapting the same to be used in the support of a form for a concrete girder of any cross sectional dimensions within ordinary range and also in the support of a form for a girder with diverging sides disposed at any angle.

A further object of my invention is to provide a form support of the character mentioned, the joist supporting portions of which will be of such construction as to be adapted to be vertically adjustable, thereby obviating the necessity, in jacking up of the floor joists, of wedges and other additional timbers as is the means ordinarily employed to effect such purpose.

A still further object is to provide a form support as mentioned which will be strong and durable, comparatively simple of construction, hence of low cost to manufacture.

Other objects will appear hereinafter.

With these objects in view my invention consists in a form support characterized as above mentioned and in certain details of construction and arrangement of parts all as will be hereinafter fully set forth and particularly pointed out in the claims.

My invention will be more readily understood by reference to the accompanying drawings forming a part of this specification, and in which,

Figure 1 is a front elevation of my device in its preferred form, illustrating its application. Fig. 2 is a side elevation thereof. Fig. 3 is a top plan view thereof detached. Fig. 4 is a detail perspective of one of the guides of the members embodied in my device for supporting the floor joists and the sides of the girder form. Fig. 5 is a detail perspective of the means embodied in my in-

vention for locking the supporting members, mentioned in the description of Fig. 4, in vertical position. Fig. 6 is a sectional detail of a portion of the member shown in Fig. 5, and Fig. 7 is a detail perspective of one of the members engaging the lower portions of the supporting members mentioned in the descriptions of Figs. 4 and 5.

Referring now to the drawings 1 indicates an upright or timber of any suitable dimensions and preferably square in cross section, upon which is supported the essential parts of my device. In order to facilitate exact vertical adjustment of said upright wedges 2 are provided at the lower extremity thereof upon which the same rests. Resting upon, and snugly fitting the upper end portion of said upright 1 is a cap 3, preferably of cast metal. Said cap is comprised of the rectangular upper portion or cap proper 4, the elongate portions of brace rods 5 depending from each of the corners of the latter, and an encircling band 6 provided at the lower extremity of said portions 5. Projecting from and preferably formed integrally with the cap portion 4 are horizontally disposed alining arms 7 of any suitable length. 8 indicate brace rods extending between and preferably formed integrally with the extremities of the arms 7 and the cap portion 6. Resting upon said cap 3 and arms 7 is an elongated timber 9 and on timber 9 rests the base member 10 of the girder form, the timber 9 being slightly longer than the member 10 is wide. In order that said timber 9 may be readily and easily secured in place upon said arms and cap, I preferably provide the top wall 11 of the latter with elongate slots 12. By such provision nails or the like may be driven through said timber and said slots into the upper extremity of the upright 1, such being the preferred means employed for securing said timber in position.

In order to support the side members 13 of the girder form and the extremities of the floor joists 14, similar elongate members or bars 15, and preferably rectangular in cross section, are provided. Said members 15 are slidably mounted in rectangular slots 16 provided in similarly formed guide members 17, the latter being detachably secured to the arms 7 of the cap 3, by means of an angular slot forming arms 18 rearwardly projecting from either thereof, the slots 19

formed by said arms being adapted to snugly receive said arms 7. By such construction the members 17 may either be elevated from engagement with the arm 7 and thus be detached, or be slid horizontally to the extremities thereof to effect disengagement. The slots 16 are of a width slightly greater than that of the members 15, thereby permitting of the latter extending through said slots obliquely or at an angle. The advantage of such construction will become obvious as the description proceeds. To facilitate locking said guide members 17, and hence the members 15 against lateral movement from the central support 1, I provide threaded rods 20, the inner extremities 21 of which are pivotally secured to the cap portion 4 by their being looped around an eye 22 provided upon and projecting from said cap. Loosely resting upon each of said rods is a washer 23 and threaded thereon a nut 24. Said rods are adapted to rest in channels 25, tapering in form, formed by substantially parallelly extending ears 26 forwardly projecting from either of said members 17, the washers 23 being adapted, when said rods are so positioned, to rest against the extremities 27 of said ears, the same being locked in engagement therewith by said nuts 24, as clearly shown in Fig. 3. To guard against accidental displacement of said washers from engagement with said ears, I provide the end surfaces 27 of the latter, upon the outer edges thereof with projections 28, such projections obviously facilitating such purpose. By such construction the lateral adjustment of the members 15 is readily effected thereby adapting my device for use in the construction of a girder of any width. 29 indicate similarly formed locking devices, the purpose of which is to lock said members 15 in vertical position. Said members 29 are adapted to be detachably secured to the arms 7 by means of hooked portions 30 rearwardly extending from the body portion 31 of said members, said hooked portions being adapted to engage said arms as clearly shown in Fig. 2. Having their extremities pivotally secured in the bifurcating lower end portion of the member 31 are laterally extending slotted members 32, the slots 33 provided therein extending obliquely therethrough. Said slots are adapted, when said devices 29 are positioned upon said arms, as shown in Fig. 1, to receive the lower end portions of the members 15, said slots being of a width slightly greater than that of the latter. Because of said slots 33 being obliquely disposed, the members 15 may be readily elevated to any position but will be locked against vertical movement in any position to which they may be adjusted, it being clear that the edges 34 and 35 of said slots 65 will, because of the weight of said members

15 be forced into engagement with the lateral edges thereof; thereby causing the locking of said members against downward movement. By such construction, the greater the weight of the members 15 or weight applied thereto, the more secure will be the gripping or clamping thereof, an advantage which will be obvious from the following. Upon desiring to lower said members 15, it is only necessary to slightly raise, as by tapping, 70 the free extremity 32' of the members 32, whereupon the clamping edges 34 and 35 thereof will obviously be disengaged and said members 15 will drop, because of their own gravity. 80

36 indicate threaded rods, the inner end portions 37 thereof being looped around an eye 38 formed upon and projecting from the cap portion 6.

39 indicate substantially U-shaped members, a perforation 40 extending through one of the arms of either of said members being adapted to loosely receive the rods 36. Said members 39 are adapted to snugly receive, between the parallelly extending arms thereof, the lower end portion of the members 15. Nuts 41 threaded upon said rods 36 adapted to abut the members 39 serve an obvious purpose. In order to insure positive engagement of said members 39 with said members 15 I preferably provide either of the latter upon the inner edge thereof with a plurality of projecting pins 42, the latter being adapted to engage perforations 43 provided in the contacting surface of said 100 first named member.

44 indicate stops provided at the extremities of the rods 36 to prevent displacement of said members 36.

In order to adapt the members 15 to support the extremities of the joists 14 the upper end portions thereof are provided with longitudinally extending angular arms 45 detachably secured thereto by means of bolts 46 extending therethrough and nuts 110 threaded upon said bolts, the extremities of the joists being adapted to rest in the slots formed by said arms and the end portions of said members 15, as clearly shown in Fig. 2. The contacting surface of the lower end portion of either of said arms 45 is provided with a projecting, transversely extending ridge 48, the same being adapted to be snugly received in a correspondingly shaped recess 49 provided in either of the members 15 for the reception of the same. By such construction a rigid securing of the arm 45 to the member 15 is effected. In order that such arms 45 may be adjusted in different positions upon said members 15 each of the latter is provided with a plurality of such recesses 49 and perforations 50 to receive the bolt 46, thereby permitting of the employment of my device with joists of any width. 115 120 125 130

It will be seen that by means of nuts 24 and 41 on rods 20 and 36, the bars 15 may be adjusted angularly and laterally, and by means of bolts 46, adjusted vertically, thus giving the three necessary adjustments required to adapt bars 15 to use on different sizes and shapes of girders. Moreover, by drawing the upper ends of bars 15 together by means of nuts 23, and forcing their lower ends apart, by means of nuts 41, intense pressure may be exerted on the form sides, if desired.

While I have shown what I deem to be the preferable form of my invention, I do not wish to be limited thereto, as there might be many changes made in the details of construction and arrangement of parts without departing from the spirit of my invention. And though I have designed my device with special reference to the supporting of girder forms, I may use the same in any other connection to which it is applicable.

Having described my invention what I claim as new and desire to secure by Letters

25 Patent is:

1. In an apparatus of the class described, the combination with an upright, of a cap detachably mounted thereon, horizontally disposed alining arms projecting from opposite sides of said cap, vertically slotted members slidably mounted upon said arms, elongate bars slidably mounted in the slots in said members, means whereby said bars will be normally locked against downward movement, means, in connection with said slotted members adapted to lock the same against lateral movement upon said arms, and means in connection with the lower end portion of said bars whereby the angular disposition of the latter may be regulated, substantially as and for the purpose specified.

2. In an apparatus of the class described, the combination with an upright, of a cap detachably mounted thereon, horizontally disposed alining arms projecting from opposite sides of said cap, vertically slotted members slidably and detachably mounted upon said arms, elongate bars slidably mounted in slots in said members, obliquely mounted in slots in said members, slotted means in detachable connection with said bars adapted normally to lock said bars against downward movement, adjustable means in connection with said vertically slotted members adapted to lock the same against lateral movement, and means in operative connection with the lower end portion of said elongate bars for adjusting the angularity thereof, substantially as and for the purpose specified.

3. In an apparatus of the class described, the combination with an upright, of a cap detachably mounted thereon, horizontally disposed alining arms projecting from opposite sides of said cap, braces for said arms, vertically slotted members slidably and de-

tachably mounted upon said arms, elongate bars slidably mounted in the slots in said members, joist seats formed in the upper end portions of said bars, means adapted for locking said bars in any elevated position against downward movement, elongate rods pivotally secured to said cap, nuts threaded upon said rods adapted to engage said vertically slotted members, and a second pair of rods and nuts threaded thereon adapted, to adjust the angularity of said bars, substantially as and for the purpose specified.

4. In an apparatus of the class described, the combination with an upright, of a rectangular cap detachably mounted thereon, depending bracing means for said cap, horizontally disposed alining bars projecting from and formed integrally with said cap, integral braces for said arms, vertically slotted members slidably and detachably mounted upon said arms, elongate bars slidably mounted in the slots in said members, angular joist-seat forming arms longitudinally adjustable upon the upper end portion of said bars, slotted means in detachable connection with said first mentioned arms adapted for locking said bars in any elevated position, elongate rods pivotally secured to said cap, nuts threaded upon said rods adapted to engage said vertically slotted members, a second pair of rods and nuts threaded thereon in connection with the lower end portion of said bars, substantially as and for the purpose specified.

5. In a device of the class described, the combination with an upright, of horizontally disposed arms projecting from said upright, a pair of members slidably mounted on said arms and provided with vertically disposed slots, pressure arms extending through said slots, locking members slidably mounted on said arms adjacent said slidably mounted members and comprising a portion recessed to receive said horizontal arms and a portion pivotally connected to the first said portion and provided with a slot to receive said pressure arms, and means for adjusting the first said members on said horizontal arms and means for spreading the lower ends of said pressure arms, substantially as described.

6. In a device of the class described, the combination with an upright, of horizontally disposed arms projecting from said upright, members slidably mounted on said horizontal arms and provided with vertically disposed slots, means for adjusting said members toward or from each other, pressure arms extending through said slots, means for spreading the lower ends of said pressure arms, a second member slidably mounted on said horizontal arms adjacent each of the first said members and a portion pivotally connected thereto and extend-

4
ing beneath the first said members, said portions being provided with slots extending diagonally therethrough to receive said pressure arms whereby said arms may be readily raised but securely locked against downward movement, substantially as described.
In testimony whereof I have signed my

name to this specification in the presence of two subscribing witnesses.

CHARLES M. MARKHAM.
